UNITED STATES PATENT OFFICE

2,454,953

SAW FITTING DEVICE

Thomas Stennitt, Lansdowne, Ontario, Canada

Application June 16, 1947, Serial No. 754,989

5 Claims. (Cl. 76—46)

1

This invention relates to saw fitting tools. Many devices have heretofore been proposed for fitting or conditioning saws, i. e., for use in performing the periodical jointing, setting, gauging and sharpening of saw teeth. Most of such devices are of a relatively complicated and cumbersome nature.

It is an object of this invention to provide a simple compact tool for use in performing all of the aforementioned operations and which is of such small dimensions that it may be conveniently carried about on the person for available use at all times.

The invention will be described with reference to the accompanying drawing, in which—

Figure 1 is a plan view of a saw fitting tool in accordance with the invention,

Figure 2 is a side elevation,

Figure 3 is a side elevation illustrating the operation of one part of the tool,

Figure 4 is a side elevation showing the operation of another part of the tool, and

Figure 5 is a side elevation illustrating another operating function of the tool part shown in Figure 4.

In the drawing, 1 is a base or anvil portion of the tool comprising a rectangular block of metal, the dimensions of which preferably do not greatly exceed five inches in length and one inch in width. The upper surface of the block is marginally bevelled on at least three sides to provide end bevelled surfaces 2 and 3 and a longitudinal bevelled surface 4. The degree of bevel of surface 3 is somewhat greater than that of surface 2 and corresponds to a normal degree of set for saw teeth when adapted to be employed in cutting soft wood. The degree of bevel of surface 2 corresponds to a normal degree of set for saw teeth when adapted to be employed in cutting hard wood. Appropriate indicating characters H and S, as shown, may be provided on the respective end of the block to provide a convenient means for locating the desired surface 2 or 3.

Removably fixed to the side surface of the block adjacent the bevelled surface 4 is a channel-shaped member 5 with its open face upwardly disposed. The attaching means may comprise a pair of pins 6 mounted in the block and adapted to extend through openings 7 in the member 5, and wing nuts 8 for engagement with the threaded end portions of the pins.

The member 5 has a cut out portion 9 in the web and adjacent leg portions of the member.

The edge of each leg of the member 5 has a projecting portion or portions 10, the edges of

2

which lie in the same plane and which provide recessed edge portions 11 and 12 adjacent the ends of the member. The edges 11 at one end of the member lie in a plane spaced a predetermined distance from the plane of the edges of portions 10 and corresponding to a degree of saw set for soft wood sawing, for instance. At least one of the legs at the other end of the member has a projection 13, the edge 14 of which lies in a plane spaced a predetermined distance from the plane of the edges of portions 10 and corresponding to a degree of saw set for hard wood sawing, for instance. In other words, edges 11 and 14 lie in slightly different planes. Indicating characters H and S may be provided on the corresponding faces of member 5 at the respective ends thereof. It is proposed that one leg of the member with its end edge portion 11 serve as a gauge for soft wood sawing and the other leg 10 of the member with its end edge portion 14 serve as a gauge for hard wood sawing, the opposite end portion of the other leg being cut away as indicated at 15 to facilitate ease of operation.

In use, the jointing operation is performed 25 with the assembled tool as shown in Figures 1 and 2, the member 5 being utilized as a vice for clamping a file 16 between the legs of the member and in right angular relation to the upper face of the block. The saw to be fitted, indicated 30 at 17, is then applied to the upper face of the block with its teeth in engagement with the file and reciprocated to perform the jointing operation. The bevelled surface 4 provides a recess to receive the downwardly projecting teeth. Spikes 18 may be provided on the bottom surface of the block to facilitate rigid positioning of the same on a fixed surface 19.

Following the jointing operation, the saw is placed on the block with its teeth overhanging one or other of the bevelled surfaces 2 and 3, as 40 shown in Figure 3, and the alternate teeth hammered down into engagement with such surface to perform the setting operation.

The sharpening operation is then proceeded 45 with by removing the member 5 from the block and placing it on the saw with the legs on either side of the saw and the web engaging the teeth thereof, as shown in Fig. 4. A series of the saw teeth, indicated at 20, will project through the 50 cut out portion 9, the longitudinal edges 21 of which are spaced from the top plane of the teeth a distance substantially equal to the desired height of the saw teeth. The series of teeth 20 are then filed in the usual manner and 55 the operation repeated by progressively moving

the member 5 along the saw. The edges 21 are tempered to withstand injury by contact with the file.

The set of the saw teeth may be gauged by placing the member 5 on the saw with its appropriate end portion 11 or 14 overhanging the teeth, as shown in Figure 5.

There has thus been provided a simple tool for use in performing all requiring saw fitting operations. Moreover, since the overall length and width of the tool need not exceed 5 inches and 1½ inches, respectively, it may be conveniently carried in the pocket of an operator for availability of use at all times.

What is claimed is:

1. A saw fitting tool comprising a metal block having a plane upper surface and a marginal bevelled surface at each end of the block in contiguous relation to said upper surface, said bevelled surfaces being at different degrees of angularity, a channel member having flat parallel legs and a web connecting said legs, and means removably securing the channel member to a lateral face of said block in longitudinally arranged relation thereto with the free ends of the legs in upwardly disposed position, the outer surface of one of the legs being in abutting relation to said lateral face.

2. A saw fitting tool as defined in claim 1, said block having a bevelled marginal surface extending longitudinally thereof in contiguous relation to said upper surface and adjacent said lateral face.

3. A saw fitting tool comprising a metal block having a plane upper surface and a marginal bevelled surface at each end of the block in contiguous relation to said upper surface, said bevelled surfaces being at different degrees of angularity, and a channel member removably secured to a lateral face of said block, said channel member having portions of the edges of both of its legs lying in a common plane, a portion of

the edge of at least one of the legs adjacent its end lying in a plane spaced inwardly a predetermined distance from said common plane, and a portion of the edge of the other of the legs adjacent its end lying in a plane spaced inwardly a predetermined distance from said common plane, said last predetermined distance being greater than said first predetermined distance.

4. A saw fitting tool as defined in claim 1, said channel member having a portion of the web and adjoining portions of the legs removed to provide a recess of uniform depth, the longitudinal edges of said recess lying in a plane spaced from the plane of the inner surface of said web a distance substantially equivalent to a desired height of saw teeth.

5. A saw fitting tool as defined in claim 1, wherein said securing means comprises a pair of longitudinally aligned pins fixed to said lateral face of the block and projecting outwardly therefrom, said legs of the channel member having aligned openings therein to receive each pin, the outer ends of the pins being threaded, and nuts engaging said threaded ends to secure the channel member to the block and to apply pressure to said legs to urge them towards each other.
